CLAIM

The ornamental design for a receptacle for electric motor, as shown and described.

DESCRIPTION

FIG. 1 is a front-top perspective view of the receptacle for electric motor in use condition, showing our new design.

FIG. 2 is a front-top perspective view of the receptacle for electric motor thereof.

FIG. 3 is a front-bottom perspective view thereof.

FIG. 4 is a front elevation view thereof.

FIG. 5 is a back elevation view thereof.

FIG. 6 is a top plan view thereof.

FIG. 7 is a bottom plan view thereof.

FIG. 8 is a left side elevation view thereof; and,

FIG. 9 is a right side elevation view thereof.

In the drawing, the broken line represents unclaimed environment only and forms no part of the claimed design.
